6 Claims. (Cl. 209—329)

This invention relates to shaking machines, for example, resonance screens or other such shaking machines, which are designed as two-body systems. On the one hand, there is the material handling member, such as a screen box and which is resiliently supported as by isolating springs, and on the other hand, there is a countermass which is resiliently connected as by means of springs with the material handling member, and interposed between the material handling member and the countermass, is an energy storage spring means. Such shaking machines are known.

The invention provides a new arrangement of the countermass. According to the invention, the countermass is U-shaped and can straddle the material handling member with its legs in such a manner that the legs extend in the direction of vibration. The energy storage springs can be disposed in recesses in the limbs and the vibratory drive can be mounted on the crossmember of the U-shaped countermass straddling the screen box.

This design and arrangement of the countermass makes it possible to build low, light shaking machines, and, since the countermass is very rigid due to its U-shape, also to utilize a light countermass so that, especially in the case of ratios of working body weight to countermass of more than 1, especially low machine weights can be realized.

Thus, the invention provides a shaking machine comprising a spring mounted handling member, a countermass member resiliently mounted on the material handling member, a storage spring operatively interposed between the countermass and the spring mounted material handling member, and means for imparting vibrating motion to one of said members for transmission of vibrating motion to the other of said members through said storage spring. By this arrangement, said members vibrate 180° out of phase with respect to each other. The shaking machine of the invention is characterized in that the countermass member is U-shaped and is disposed with one leg thereof on either side of the material handling member with the crossarm thereof extending across the material handling member. The legs are disposed in parallel relation and substantially in the direction of vibration.

In a preferred construction according to the invention, recesses are provided in the legs and storage spring elements are disposed in the recesses. A crossarm is rigidly secured to the material handling member and end portions thereof extend into the said recesses. The storage spring elements are operatively disposed between the material handling member crossarm end portions and the countermass in the recesses.

The means for imparting vibrating motion to the system can be an imbalance drive for imparting rectilinear vibration to the material handling member and the countermass. Desirably, the means for imparting vibration is an oscillatory drive working on the crossarm which is rigidly secured to the material handling member.

The invention is further described in the accompanying drawing, wherein:

FIG. 1 is a schematic view, in elevation, of apparatus according to the invention;

2

FIG. 2 is a plan view of the apparatus shown in FIG. 1; and

FIG. 3 is a view taken along line 3—3 in FIG. 1.

In the various figures of the drawing, like reference characters indicate corresponding parts.

The shaking machine shown in the drawing is a resonance shaking screen and comprises the screen box 1 which represents the material handling member of the vibrating system, and the countermass 2. The screen box 1 is supported resiliently upon support springs 3 and bears the screen mesh 4. The countermass 2 has a U-shape, straddles the screen box with its legs 5, and is linked by means of springs 6 to the screen box 1 in such a manner that it is disposed with its legs in the direction of vibration. Between the screen box and the countermass are disposed the energy storage springs 7, which store and release the vibratory energy of the vibrating bodies 1 and 2 in synchronism with the rate of vibration. Bodies 1 and 2 and the energy storage springs form together a two-body vibrating system in which, as it is known, the bodies oscillate 180° out of phase with one another.

The energy storage springs 7 are fastened to the ends of a crossarm 8 which is rigidly affixed to the screen box 1 by supports 20, and extend into recesses 9 in the legs 5 where they stand opposite and clear of the bumper plates 10 affixed to the countermass legs. If desired, the energy storage springs 7 can be fastened in the recesses 9 and the bumper plates 10 on the crossarm 8. Screen crossarm 8 and countermass crossarm 12 are preferably arranged above the side members 1a and 1b of the screen box 1, in order to obtain the highest possible clearance for the material being screened.

The arrangement of the countermass 2 on the screen box 1 is such that the straight line which connects the centers of gravity S_K and S_G of the screen box and countermass, respectively, and on which the combined center of gravity S lies, extends parallel to the direction of vibration of the system.

The drive 11, a crank in the present case, is disposed on the crossmember 12 of the U-shaped countermass straddling the screen box 1, and is directly connected to the screen crossarm 8 with its elastic push rod 14, which can be a spring, and passes through an opening

13. Thus, the drive is loosely coupled to the crossbeam 8 connected to the screen box. The crank drive 11 includes a shaft 21 which is rotatably received in the sliding bearings 22, and is mounted for rotation with the drive wheel 23, which in turn, is connected by belt 24 with the motor drive 25. Instead of the crank drive 11, 14, an eccentric weight drive can be used, preferably one providing rectilinear vibration.

The invention is similarly applicable to resonance vibrating machines such as feed shoes under bunkers or as vibrating conveyors.

While the invention has been described with reference to particular embodiments thereof, these embodiments are merely representative and do not set forth the limits of the invention.

What is claimed is:

1. A shaking machine comprising a spring mounted material handling member and a countermass member resiliently mounted on the material handling member, said material handling member including side members and a screen mounted within said side members, the countermass member being U-shaped disposed with one leg thereof on either side of the material handling member, and having a cross member extending across the material handling member, said side members terminating below said cross member, the legs of said U-shaped member being disposed in parallel relation and substantially in the direction of vibration, each of said legs hav-

ing means defining a recess therein, a crossarm rigidly connected with said material handling member, the end portions of said crossarm projecting into the said recesses, storage springs disposed in said recesses and operatively interposed between said crossarm and said U-shaped countermass for transfer of vibration between the U-shaped countermass member and the crossarm of the material handling member, and means for imparting vibration to said material handling member and countermass.

2. A shaking machine according to claim 1, and including an oscillatory drive for imparting vibration to the shaking machine operatively connected to said cross-arm.

3. A shaking machine according to claim 1, said countermass cross member and said material handling member crossarm being disposed above the material handling member.

4. Apparatus according to claim 1, and comprising an imbalance drive for imparting rectilinear vibration to the shaking machine and directly connected to said cross-arm.

5. A shaking machine according to claim 1, the center of gravity of the material handling member and the center of gravity of the countermass being disposed on a straight line extending substantially in the direction of vibration.

6. A shaking machine according to claim 1, the weight ratio of the material handling member to the countermass being greater than about 1.
